UNITED STATES PATENT OFFICE.

ARTHUR K. CAMP, OF MILWAUKEE, WISCONSIN.

DESIGN FOR A SPOON, &c.

SPECIFICATION forming part of Design No. 20,913, dated July 7, 1891.

Application filed April 6, 1891. Serial No. 387,881. Term of patent 7 years.

To all whom it may concern:

Be it known that I, ARTHUR K. CAMP, a citizen of the United States, residing at Milwaukee, in the county of Milwaukee and State 5 of Wisconsin, have invented and produced a new and original Design for the Ornamentation of the Handles of Spoons, Forks, and Similar Articles of Manufacture; and I do hereby declare the following to be a full, clear, 10 and exact description of the same, reference being had to the accompanying drawing, forming a part thereof.

My design is intended to be materialized in or upon the handle of a spoon, fork, or other 15 similar article of manufacture; and it consists, primarily, of the figure of a middle-aged stoutly-built beardless man standing on a block or pedestal. The figure is bare-headed and clad in a loose fitting double-breasted and 20 buttoned frock-coat, with a sash loosely tied around the waist, the two ends of said sash hanging down the right side proper of the figure, (on the left-hand side of the accompanying drawing.) The man's left arm bears 25 on the sash, depressing it from a horizontal position, and his right hand grasps the barrel of a gun, whose stock rests on the pedestal by the man's right foot, said gun being provided

with a loosely-hanging suspension-strap. The legs of the figure are covered with leggins. 30 Beneath the pedestal appear the words "Solomon Juneau," the letters of the first word being shown as strung together; but such words obviously form no part of my design.

Having thus described my design, what I 35 claim therein is—

The design for a spoon or similar article, as herein shown and described, comprising the figure of a middle-aged stoutly-built beardless bare-headed man standing on a block or 40 pedestal and clad in a loose-fitting double-breasted and buttoned frock-coat and leggins, with a sash loosely tied around the waist and the two ends of said sash hanging down one side, a gun with pendent strap, said 45 gun resting on said pedestal, and one hand of the figure grasping the gun-barrel, while the other arm of said figure bears on said sash, all substantially as shown and described.

In testimony whereof I affix my signature in 50 presence of two witnesses.

ARTHUR K. CAMP.
